UNITED STATES PATENT OFFICE.

EDWIN T. GRAY AND ALFRED T. HOEVET, OF NEW YORK, N. Y.

DESIGN FOR AN AUTOMOBILE SIGNAL-BOX.

50,127.

Specification for Design.

Patented Jan. 2, 1917.

Application filed September 1, 1916. Serial No. 118,153. Term of patent 3½ years.

To all whom it may concern:

Be it known that we, EDWIN T. GRAY and ALFRED T. HOEVET, citizens of the United States, residing at New York city, in the county and State of New York, as joint inventors have invented a new, original, and ornamental Design for Automobile Signal-Boxes, of which the following is a specification, reference being had to the accompanying drawing, forming part thereof.

The figure is a side elevation of an automobile signal box showing our new design.

We claim:

The ornamental design for an automobile signal box as shown.

EDWIN T. GRAY.

ALFRED T. HOEVET.

Witnesses:

W. M. CHRISTIE,
S. ADENBAUM.
